UNITED STATES PATENT OFFICE.

THOMAS J. YATES, OF SALEM, MASSACHUSETTS, ASSIGNOR TO YATES MACHINE COMPANY, OF SALEM, MASSACHUSETTS, A CORPORATION OF MASSACHUSETTS.

STRIPPER DEVICE.

1,186,640.

Specification of Letters Patent. Patented June 13, 1916.

Application filed October 19, 1915. Serial No. 56,771.

To all whom it may concern:

Be it known that I, THOMAS J. YATES, a citizen of the United States, residing at Salem, county of Essex, State of Massachusetts, have invented an Improvement in Stripper Devices, of which the following description, in connection with the accompanying drawing, is a specification, like characters on the drawing representing like parts.

This invention relates to improvements in stripping means to be used particularly in connection with laundry machines for ironing flat work.

The present form of ironing machine which is adapted to iron flat work such as towels, sheets, etc., has usually a series of cloth covered rolls journaled above a steam-heated chest, the surface of which immediately beneath each roll is usually concaved to secure greater ironing contact. These rolls are revolvably actuated and usually function in connection with an endless apron to pass the articles over the heated surfaces. In these machines difficulty is encountered in efficiently preventing the articles, passed between the rolls and the concaved surface, from following the surface of the roll in its revolution instead of passing onward in the desired proper course over the ironing chest. At present a plurality of strings or cords, each transversely embracing the whole series of rolls, is employed to overcome this disadvantage.

These cords rapidly deteriorate and break, entailing a stoppage of the whole machine for their replacement. As approximately six operatives are employed in connection with each set of rolls, the loss entailed by this disadvantage alone is considerable. Further, disfiguring creases caused by these cords are left in the finished work. Heretofore, it has been attempted to overcome these disadvantages by employing a rigid metallic plate extending longitudinally each roll, the edge of the plate being in contact with the cloth covering of the roll adjacent the junction of the roll and the heated sur-

face. This type has generally been discarded as defects develop in that the articles being ironed would catch at different points on this metal doffing plate with the result that the articles would become jammed between the plate and the roll. And these plates similarly and more quickly wore out the cloth covering of the roll through frictional contact therewith.

Another form of ironing machine in common use and to which this invention is also particularly applicable is the calender or upright type of machine in which a revolvably actuated heated drum is partially surrounded by a plurality of drum contacting rolls. Similar difficulties are found in this machine modified only by the character of the machine.

This invention provides a plurality of stripper fingers for each roll which are mutually independent, longitudinally flexible and pivotally mounted. Hence, the catching of an article by one of the stripper fingers will throw that stripper finger through its flexibility or pivotal mounting, out of operation and will still permit the adjacent stripper fingers properly to function and thus prevent the article either from becoming caught and torn or from following the roll.

An object of this invention, therefore, is to provide an efficient stripping means for the rolls of ironing and similar machines.

Another object is to provide a plurality of longitudinally flexible independent pivotally mounted strippers for the roll of an ironing machine.

Other objects of the invention will more fully appear from the following description and the accompanying drawings and will be pointed out in the annexed claims.

In the drawings, Figure 1 is a longitudinal sectional view of a portion of an ironing machine of the flat or horizontal type; Fig. 2 is a cross section of one of the rolls showing a stripper finger and its mounting; Fig. 3 is a front elevation showing two of the stripper fingers and an angle iron support

to which they are pivoted; Fig. 4 is a sectional detail of the pivotal mounting of the stripper finger; Fig. 5 is an underside view of the construction shown in Fig. 4, the stripper finger being shown in dotted line; Fig. 6 is a diagrammatic view showing the stripper finger as applied to an upright machine.

The ironing machine, to which this selected embodiment of the invention is shown as applied, is of the usual type and consists of a heated ironing chest 1 above which is suitably journaled a series of revolubly actuated rolls 2. The upper or ironing surface of the chest has a plurality of arcuate or concaved surfaces 3 which correspond substantially to the contour of a portion of the adjacent roll surface. Each roll has a suitable cloth covering 4. An endless apron 5 runs around the rolls 6 and 7.

The flat work is fed to the apron 5 from a suitable feed table, not shown, whence it is carried to the front roll at the right in Fig. 1 and is pressed thereby against the corresponding concaved surface 3 of the heated chest 2.

Each stripper finger, in this selected embodiment, comprises a blade 8 having a retaining member or holder 9 therefor. The blades may be formed of any suitable material but are preferably composed of resilient blue tempered ribbon steel, having a normal arcuate form to correspond substantially to the curvature of an arc of the roll surface. The lower or free end 10 of each finger is adapted normally to be positioned in light contact substantially tangentially to the peripheral cloth covering 4 of the respective roll therebelow. The upper end 11 of each blade, in the preferred construction, is attached to the holder 9. Each holder of a roll series is retained by a supporting bar 12 which extends transversely the ironing machine. These bars 12 are disposed, in this embodiment, one above each of the rolls 2, each being substantially adjacent the vertical plane through the axis of the roll and extending across the machine frame usually paralleling the corresponding roll. These bars 12 are illustrated as angle irons and may be secured at their respective ends to the usual frame sides of the machine in any suitable manner not herein necessary to be shown.

The holders 9 may be of any suitable material but are relatively inexpensively produced by casting into the desired form. In this embodiment, they are shown as having a body portion which has flanges 13 on its downwardly presented face. The upper blade end 11 is secured to this face by a rivet 14 and relative lateral or rotatory movement between the holder and finger prevented by the flanges 13 which engage the

sides of the end portion of the finger. The 65 preferably integrally cast ear 15 provides a suitable means for pivotally mounting the holder between the depending arms 16 of the bracket 17 secured by suitable rivets 18 to the angle iron bar 12. The ear is apertured to receive a pivot pin, the end portions of which are held by the bracket arms 16.

As the strip steel blade is of such light weight that a very slight tension will throw 75 the finger away from the cloth covered roll 2, it has been found desirable to provide a means assuring a light yet readily yieldable contact. A downward pressure upon the upper end portion of the finger effectually 80 achieves this result and a simple means of its attainment is to form the holder with an enlarged integral portion constituting a weight 19 which preferably is formed to extend over the finger and functions to assure 85 a yieldable contact. This weight 19, being adjacent the pivotal line of the finger, does not greatly hinder the throwing out of the finger when it functions improperly.

The operation of this structure is efficiently simple. Taking for example small articles such as napkins or towels, they are fed to the endless apron 5 with a plurality of articles abreast, and, passing between the front roll 2 and its opposed concaved 95 portion of the steam chest, the tendency of the articles in their moist condition is to follow around or to adhere to the roll 2. Several of the roll-contacting lower ends 10 of the stripper fingers, which are relatively numerous and spaced close together on this front roll, engage each of the articles and strip them from the roll. Should a portion of an article catch one of the fingers, the remaining fingers engaging the same article would effectually strip the article from the roll. The obstructed finger, readily yielding through its flexibility and through its pivoted weighted holder, would be swung away from the roll and article and 110 become readily released—to be returned immediately to normal shape and position of roll contact by the resiliency of the finger material and by gravitational force acting through the weight 19. The towels or other 115 flat work are then carried onwardly and held in contact with the successive ironing surfaces by the revolubly rolls 2. As the towels or other flat work near the rear of the machine, they become more nearly dry 120 and tend the less to adhere to the successive rolls.

The flat work articles at the beginning of the ironing operation are relatively moist and have greater tendency to stick to the 125 cloth cover 4 of the front roll than they have to the rolls with which they later contact in this drying and ironing process.

Therefore, relatively fewer stripper fingers are required at the rear rolls than at the ones near the front or feed end of the ironing machine. Hence, from the rear to the 5 front of the machine the number of stripper fingers per roll preferably is progressively increased and it results that the space between the adjacent stripper fingers on each roll is correspondingly decreased and the 10 stripping function thus augmented at the front or feed end.

The flat work at the extreme rear end after being stripped from the rearmost roll is further dried and folded or otherwise 15 treated in the usual manner.

An adaptation of this selected embodiment of the invention to the ordinary so-called upright machine is shown diagrammatically in Fig. 6. Therein, is shown the 20 usual revolvably actuated heated drums 20 and 21, a feed table 22, a plurality of drum-contacting rolls, which function to hold the flat work received from the feed table in contact with the revolvble heated drum 25 whereby the work is passed around the upper portion of the drum periphery whence the work passes to the downwardly moving adjacent portions of the endless apron 23 which carries the work to the lower heated drum 30 and thence guided around the drum 21 by a second similar apron 24 to the folding table 25. Stripper fingers embodying this invention are provided for the upper drum-contacting rolls. However, in the 35 case of rolls located as are the rolls 26 and 27 where the lower end of the stripping finger must assume a roll-contacting position at or beyond the vertical plane of the drum axis, it is obvious that the weight 19 must 40 assume a position well beyond the pivot of the finger holder and at such angle to the arc of the finger that the resultant effective force will be exerted to hold the lower finger ends in the requisite light and yielding drum contact. This is effected simply by elongating the body 9 of the holder and making it of 45 sufficient weight to give the desired pressure at the roll surface.

There is thus provided an inexpensive, 50 simple highly efficient stripping means which may be fitted to the present types of ironing, calendering and like machines with few and easily effected structural changes in the machines. The use of strings or cords 55 is eliminated, and delays entailed by stopping the machine are practically negligible. And with this type of stripper, damage to fine fabrics, fringes, embroiderings and borders is minimized as the flexible nature of 60 the stripping fingers admits of maximum yieldability.

In both types of machine the rolls are padded and covered with cloth, and this covering wears or becomes torn so that it is

occasionally necessary to recover or repair 65 one or more of the rolls. The stripping mechanism of this invention eliminating the use of strings or cords running around a plurality of the rolls, and being itself a unitary structure with respect to each roll enables 70 a single roll to be repaired or recovered without disturbing the other rolls.

It is to be understood that the construction disclosed herein is illustrative but not restrictive and that various modifications 75 may be made within the scope and meaning of the claims which follow.

Having fully described my invention, what I claim as new and desire to secure by Letters Patent is:

1. A stripper for ironing rolls comprising a finger and a support therefor positioned above the roll, said finger having its upper end secured to said support and its lower end in yieldable contact with the roll to 85 strip articles therefrom, said finger being resilient throughout its length whereby said contact is yieldable and upon improper functioning of the finger it may spring out of normal stripping position. 90

2. A stripper for ironing rolls comprising an arcuate finger whose lower end normally rests against a roll, said finger being resilient throughout its length, a pivotal mounting for said finger, the finger being 95 secured to said mounting at its upper end whereby full finger resiliency is retained and the finger upon improper functioning may be thrown out of working position.

3. A stripper for ironing rolls comprising an arcuate finger whose lower end normally rests against a roll, said finger being resilient throughout its length, and a weight having means for securing the upper end of the finger thereto and having an 100 extension adapted to be pivotally mounted above an adjacent roll whereby the finger is 105 pivotally supported without impairment of its resiliency and the lower end thereof is held in yieldable weighted contact with said 110 roll.

4. Stripping means for ironing rolls comprising a plurality of independent fingers, each being resilient throughout its length, a support for said fingers whereby the lower 115 ends thereof normally rest against an adjacent roll, independent means for pivotally mounting each of said fingers on said support whereby upon improper functioning of any finger it may be thrown out of working position without affecting the function of the others. 120

5. Stripping means for ironing rolls comprising a plurality of independent fingers, each being resilient through its length, a 125 support for said fingers whereby the lower ends thereof normally rest against an adjacent roll, a plurality of weights indepen-

4
ently and pivotally mounted on said support, and means for securing the respective upper ends of said fingers each to one of said weights whereby each finger is pivotally and independently supported without impairment of resiliency and held in yieldable contact at its lower end with the roll

and whereby upon improper functioning of any finger it may be thrown out of working position without affecting the function of the others.

In testimony whereof I have signed my name to this specification.

THOMAS J. YATES.
